(57)

CLAIM

An ornamental design for the oven, as shown and described.

DESCRIPTION

FIG. 1 is a first perspective view showing the front, right and top surfaces of the oven showing the design;

FIG. 2 is a second perspective view showing the front, left and top surfaces thereof;

FIG. 3 is a front elevational view thereof;

FIG. 4 is a rear elevational view thereof, wherein the broken lines form no part of the design;

FIG. 5 is a right side view thereof;

FIG. 6 is a left side view thereof;

FIG. 7 is a top plan view thereof; and,

FIG. 8 is bottom plan view thereof, wherein the broken lines form no part of the design.

1 Claim, 8 Drawing Sheets
